UNITED STATES PATENT OFFICE

2,641,917

COMBINATION DYEING AND SQUEEZING
DEVICE FOR CLOTH-DYEING MACHINES

Julien Dungler, Basel, Switzerland

Application September 11, 1946, Serial No. 696,174
In France May 20, 1946

5 Claims. (Cl. 68—22)

1

This invention refers to dyeing and like cloth or web treating machines.

The invention has for its object to provide means affording the dyeing of fabrics at full width within an extremely small space, whereby the piece of fabric, or even two superposed pieces or laps of fabric, may pass through the dye bath or baths in a continuous manner and in one and the same direction, as many times as required by the nature of the dye bath or baths.

The invention further contemplates the provision of one or a plurality of horizontal crabbing devices or padders—each comprising a pair of rollers with substantially parallel, horizontal axes, said rollers being pressed against one another by mechanical or hydraulic means, to thereby attain trough-shaped reservoirs above the respective horizontal generatrix of contact of said rollers whereby the fabric is led in a spiral path passing several times, in the same direction, through the horizontal crabbing device or devices, and leaves the same, after having been subjected to a final squeezing action.

Preferably, the spiral path of the fabric is so arranged as to leave a central space having a zone of greater width than that of the fabric, in such a manner that the feed of said fabric is effected in said zone where there is furthermore provided a direction changing member which enables the fabric to start on its spiral path or course.

Embodiments of the invention are given merely by way of non-limitative examples and are illustrated diagrammatically in vertical section in the accompanying drawings to which reference will be made in the ensuing description.

In said drawings:

Fig. 1 shows a machine with a single horizontal crabbing device or padder made in accordance with the invention;

Fig. 2 a machine with two horizontal crabbing devices;

Figs. 3 and 4 show a modified embodiment of the invention in vertical sectional elevation and a top plan view, respectively.

In the machine of Fig. 1, reference numerals 1 and 2 designate two horizontal rollers with axes thereof in the same horizontal plane, which rollers are held in contact with one another under pressure and in the plane in which their axes lie. These rollers form between them a trough with cylindrical side walls to serve as a dye reservoir 3. The liquid-tightness at the end may be obtained in the manner described in copending application Serial No. 694,273 filed August 31, 1946, now U. S. Patent No. 2,603,077,

2

dated July 15, 1952. According to this latter application the crabbing device is provided at each end of the pair of rollers, with a liquid-tight cheek or flange 4, mounted on the shaft of one of the rollers, and of sufficient diameter and size to form a flat end wall for the dye reservoir thus created, said cheek being pressed by spring or other means against the respective end surfaces of the said rollers.

10 This horizontal crabbing machine is combined with means whereby the fabric 5 effects a spiral path or course, which is so arranged that the fabric is conducted to pass repeatedly (twice only according to the diagrammatic showing of Fig. 1) through the dye bath or reservoir 3 and, after having passed the same the last time and after having been subjected to a final squeezing action between the rotary rollers 1 and 2, comes out of the machine and passes, for example, into a mechanical folding device 11.

15 The fabric 5, which is brought into a vertical plane located laterally with respect to the spiral path, and which is controlled by selvedge-guiding-roller devices 10, is guided by external horizontal guide-roller 6 into the central space 7 left inside the convolutions of the fabric, then deviated by another horizontal guide-roller (or a bar) 8 arranged at 45°, and passes over the first of the guide-rollers 9 and then effects the course indicated by the arrows.

20 In the embodiment of Fig. 2, two horizontal crabbing devices 1—2, 1'—2' forming dye troughs or reservoirs 3, 3', are combined with a device for continuously circulating the fabric or web 5 with three convolutions and so that it passes, at each convolution, through each of the troughs 3 and 3', the outlet of the web taking place after it has passed for the third time through the trough 3' and, the last squeezing action has been effected by the rollers 1'—2'.

25 In the modified construction of Figs. 3 and 4, the bottom 12 of the machine forms, below each crabbing device and in close proximity thereto, a trough 13 and 13' respectively, of small capacity.

30 When thin fabrics are treated which require to be passed several times, it is possible to use as dye troughs the two trough-reservoirs of each pair of rollers. On the other hand, when several superposed layers provide a thickness of fabric which is so great that there is a risk of the rollers getting out of contact on either side of the selvedges, it is advisable to use the troughs 13 and 13' as dye reservoirs.

35 In Fig. 3 numeral 14 designates a receptacle containing the dye; 15 and 15' are the supply

pipes for the two crabbing devices; in case the troughs 13 and 13' are used, the dye supplied by the pipes 15 and 15' between the rollers 1, 2 and 1', 2' may drop for collection into the said troughs 13 and 13'.

For pressing the rollers 2, 2' against the rollers 1 and 1' respectively, a hydraulic device is provided which comprises, on each side of the machine, a cylinder 16 and two pistons therein having rods 17 and 17' respectively.

The drive of the rollers 1 and 2, and also of the folding device 11, is effected by a motor 18.

It is of course understood that the invention is in no way limited to the particular embodiments shown and that it is possible, without exceeding the scope of the invention, to imagine further improvements of details.

Having thus described the invention, what is claimed as new and desired to be secured by Letters Patent, is:

1. In a dyeing and like treatment machine for web material; the combination of two pairs of substantially horizontally extending rollers, with guide means for said material, the rollers of each pair of rollers being in contact with each other along a generatrix of said rollers, one roller of each pair of rollers being provided with end flange means to thereby form between each pair of rollers and said flange means a reservoir adapted to contain a treatment liquid for said material, one pair of rollers being spaced from another pair of rollers, said two pairs of rollers being located substantially in a common horizontal plane, said guide means being adapted to conduct said material to and from said pairs of rollers so that said material follows a spiral course from one pair of rollers to the other pair of rollers and travels in superposed layers through said reservoirs and for final discharge from one of said reservoirs.

2. In a dyeing and like machine for treating web material; the combination of two pairs of rollers having substantially horizontal axes, the rollers of each pair of said rollers being in contact with each other along a common generatrix, with guide means for said material, each pair of rollers including end flange means to thereby form between the rollers in contact with each other and said flange means a respective reservoir adapted to contain a treatment liquid for said material, at least part of said guide means being accommodated intermediate said pairs of rollers, whereby said material may be conducted to said part of said guide means and then deviated by the latter to follow a spiral course with respect

to said pairs of rollers and to travel in superposed laps through said reservoirs.

3. In a dyeing and like machine according to claim 2, wherein said pairs of rollers are arranged substantially in a common substantially horizontal plane.

4. In a dyeing and like machine according to claim 2, wherein a receptacle is arranged below each pair of rollers, each receptacle being adapted to contain a further treatment liquid, said pairs of rollers being adapted to form squeezing rollers for said web material leaving said receptacles, respectively.

5. In a dyeing and like machine for treating web material; the combination of at least one pair of substantially horizontally extending squeezing rollers in contact with each other along a common generatrix, with guide means for said material, said pair of rollers including end flange means to thereby form above said generatrix and between said rollers and said flange means a reservoir, said reservoir being adapted to contain a treatment liquid for said material, a part of said guide means being arranged above and laterally from said pair of rollers and being adapted to conduct said material from above into said reservoir and between said rollers, thence over other of said guide means below said rollers, and from further of said guide means in a spiral path back into said reservoir whereby said web material is arranged in superposed layers therewithin, the remainder of said guide means being adapted to finally lead said web material from below said reservoir and after squeezing operation between said rollers to a collecting station.

JULIEN DUNGLER.
